DESIGN FOR A CASE FOR EAR PROTECTORS OR OTHER ARTICLES

Paul C. Perrin, Pittsburgh, Pa.

Application September 19, 1940, Serial No. 95,195

Term of patent 14 years

To all whom it may concern:

Be it known that I, Paul C. Perrin, citizen of the United States, residing at Pittsburgh, in the county of Allegheny and State of Pennsylvania, have invented a new, original, and ornamental Design for a Case for Ear Protectors or Other Articles, of which the following is a specification, reference being had to the accompanying drawing, forming a part thereof.

Fig. 1 is a top plan view of a case for ear protectors or other articles embodying my new design;

Fig. 2 is a side elevational view thereof; and
Fig. 3 is an end elevational view thereof.

I claim:

The ornamental design for a case for ear protectors or other articles, substantially as shown.

PAUL C. PERRIN.
